HARRY W. KULP AND MARTIN C. DELLINGER, OF LANCASTER, PENNSYLVANIA

BUSHING REMOVER

Application filed May 30, 1931. Serial No. 541,130.

This invention relates to bushing removers and is primarily intended for use in removing the valve-stem bushings as used in some automobile engines in recent years and now in extensive use.

In the type of automobile engines in question the valve-stems have an enlarged lower end and said stems are centered in their usual guides by longitudinally split cylindrical bushings inserted in the guides after the valve-stems have been inserted in position, said bushings being normally held in place by the upper ends of the usual valve springs.

Because of the foregoing construction, in order to remove the valve for replacement or for grinding, etc., it is not only necessary to free them from their respective springs, but it is also necessary to remove the bushings in order to permit the upward withdrawal of the lower ends of the respective valve-stems. Necessarily the springs will be bodily removed but even when freed of the action of their cooperating springs the bushings will remain in normal position in an engine that has been in use, due to the action of heat and the formation of carbon and accumulation of gummy oil or oil residue and the like, so that said bushings must be thrust or pulled out of the guides while the valve-stems are interposed between each respective pair of semi-cylindrical bushings.

The primary objects of the invention are to provide a simple preferably stamped sheet metal tool adapted to straddle the valve head and fit about the valve-stem and to extend through the usual engine block intake or exhaust ports so as to engage upon the upper end of the bushings to be removed, said tool comprising a heavy preferably cast metal hammer receiving or driving head; to provide such a tool so formed at all portions of its respective sheet metal members that the various portions will cooperate with each other to resist deformation under the shock of hammer blows in the ordinary use of the tool; to provide such a tool a cooperating pair of sheet metal members in combination with a heavy rigid metal driving head slidably receiving the registering opposed upper end portions of said sheet metal members to hold

said members against relative spreading and to prevent the bending of said portions; to provide said driving head and the respective upper end portions of said members with interengaging portions preventing the relative turning or twisting of said portions when said portions are fully received by said driving head in the operative driving position of the latter; and, considered more narrowly, to provide a permanent sliding pivotal connection between the upper end portions of said sheet metal members and said driving head; and to obtain a very simple construction economical of manufacture and adapted to large quantity production.

In this application we show and describe only the preferred embodiment of our invention simply by way of illustration of the practice of our invention as by law required. However, we realize that our invention is capable of other and different embodiments and that the details thereof may be modified in various ways, all without departing from our said invention. Therefore, the drawing and description herein are to be considered as merely illustrative and not as exclusive.

In the accompanying drawing:

Figure 1 represents a perspective view of our improved tool with the driving head in operative driving relation;

Figure 2, a fragmentary sectional view of an engine block of the type referred to, with the valve and its stem raised and a bushing removing tool embodying our invention being shown in elevation in the course of being applied thereto, the driving head being moved to inoperative driving position to allow swinging movement between the sheet metal members, and the valve spring and lower valve spring cup being removed;

Figure 3, a view at right angles to Fig. 2, the tool being applied to the valve-stem and straddling the valve and resting on the upper end of the bushing in operative position, and the driving head being in its lower or operative driving position;

Figure 4, a fragmentary detail central cross-section taken through the driving head and adjacent portions of the sheet metal members at right angles to Fig. 2;

Figure 5, a cross-sectional view taken on the line 5—5 of Fig. 4, looking in the direction of the arrows;

Figure 6, a sectional view on the line 6—6 of Fig. 4, looking in the direction of the arrows;

Figure 7, a sectional view on the line 7—7 of Fig. 3;

Figure 8, a sectional view on the line 8—8 of Fig. 3;

Figure 9, a sectional view on the line 9—9 of Fig. 3;

Figure 10, a sectional view on the line 10—10 of Fig. 3, looking in the direction of the arrows; and

Figure 11, a sectional view on the line 11—11 of Fig. 10.

Referring now in detail to the drawing, A indicates the engine block having the usual intake and exhaust ports opened and closed by cooperating poppet-valves, such as valve B, adapted to close its corresponding port by contact with its seat H and having a valve-stem C extending through valve-stem guide F and centered therein by longitudinally split cylindrical bushing E, comprised of two cooperating semi-cylindrical members, the said valve-stem having an enlarged lower end D to receive and support the usual lower spring cup, not shown, without need for the employment of the retaining pin or key.

All of the foregoing construction mentioned in the immediately above paragraph is old and forms no part of the present invention, being illustrated generally and described briefly merely to afford the proper background to promote a quick understanding of the present invention.

The tool of the present invention comprises two preferably heavy stamped stiff resilient sheet metal thrust members and a heavy rigid metal driving head 5 the registering opposed upper end portions of the thrust members being slidably received and held together by said driving head 5. Each said thrust member comprises a lower internally channeled valve-stem receiving leg portion or shank 1 merging at an angle of approximately 45 degrees with an outwardly and upwardly disposed hood or yoke portion 2, which in turn merges at an angle of approximately 90 degrees with an upwardly and inwardly extending upper hood or yoke portion 3, which in turn merges at an angle of approximately 45 degrees with an upwardly extending driving head receiving portion 4 in substantial alignment with the foot or shank 1.

The two thrust members are associated together in opposed relation so as to approximately define a square between their opposed yoke portions to accommodate the valve head B, with their internally channeled faces of their foot or channel portions 1 opposed to

each other and adapted to receive between them and accommodate the valve-stem C.

The driving head 5 is recessed, preferably centrally and preferably for most of its length from its lower end face vertically to form a socket 11 of such length and cross-sectional size as to freely, yet snugly, slidably receive the opposed engaging upper portions 4 of the two thrust members in their normal operative driving association. Preferably said socket 11 will be formed with transversely registering centrally disposed vertically extending guide grooves 12 to receive and guide the cooperating guide and reinforcing or bracing ribs 13 formed in the portions 4 by stamping up the metal during one of the stamping operations.

If desired, and as preferred by the inventors, the driving head 5 and said opposed pair of thrust members may be permanently associated together, and such construction has been illustrated in the accompanying drawing wherein the driving head 5 has been illustrated with a pair of vertically extending central transversely registering slots 6 extending in alignment with the guiding and reinforcing ribs 13 respectively, a pin 7 extending into both of said slots and through the upper end portions of the interposed portions 4 of said thrust members and receiving washers 8 on its respective outer ends beyond the outer faces of the driving head 5 and having its respective extreme end portions riveted over or upset against said washers, being adapted to slide lengthwise of said pair of slots 6 while definitely tying the thrust members and the driving head together as a single unitary three-part tool, and thus constituting a sliding pivotal connection between said driving head and the opposed pair of thrust members. However, while such permanent association between the thrust members and between the thrust members and driving head is preferred, it is not an essential consideration of our invention considered in its broader aspects.

Each portion of each of the thrust members is of special braced construction to resist deformation under the shock of hammer blows incident to its normal use, and each portion merges with the other in an arcuate formation to strengthen the joint between the respective portions all to the end of strengthening and bracing each thrust member from end to end and to promote the combination and cooperative resistance of the two opposed thrust members when used together in their normal association during the normal use of the tool.

To accommodate the valve head B in the hood between the portions of the lower opposed hood portions 2, said portions will preferably have their outer edge portions slightly flattened out as at 9, all in the same plane, as illustrated in Figs. 1, 2 and 3.

While the two will preferably be of quite heavy sheet metal, the exterior faces of the lower portions of the feet or shanks 1 will lie either flush with, or preferably, inside of the circle defined by the inner face or bore of the bushing receiving guide F for obvious reasons.

The operation is briefly as follows:

The tool is inserted in a slanting position through the port-hole and its beveled edges 10 are forced against the valve-stem C until the shanks or feet 1 spread and straddle the valve-stem, when the tool is swung to vertical position and the driving head 5 is shoved downward to receive and bind the portions 4 together. In this position, as illustrated in Fig. 3, the lower ends of the shanks or feet 1 will be in engagement with the opposed upper ends of the semi-cylindrical bushing members E and a few light hammer blows on the top of the driving head 5 will serve to loosen and dislodge the said semi-cylindrical bushings E. Thereafter, the driving head 5 will be slid upward to the position indicated in Fig. 2, to release the portions 4 for independent relative movement and to provide for a greater free length of the thrust members with consequent greater yielding ability as well as pivotal or relative turning movement, when the tool may be pulled or removed from about the valve head and its stem, as is obvious.

Any suitable material may be used.

Also it is to be borne in mind that the article is not a highly technical or exact precision instrument, but a rough usage tool constructed largely by casting and by sheet metal stamping operations from the general run of sheet metal stock and subject to variations both in the casting and in the thickness or weight of metal in the stamped metal portions, and consequently in the degree of resiliency and in contour or form as the press and stamping dies may become worn, etc., and also in relative positions during the assembly operation, all being matters incident to large quantity production operations.

Also while it is desirable that the lower ends of the portion 1 of the tool should lie in the same horizontal plane, this is not essential, although most natural, usual and preferred.

Also, while thrust on the bushings in a direction as nearly parallel to the axis of the valve-stem as is obtainable is desirable, this is not essential, such thrust need not be exactly parallel to such axis, nor need it closely approach parallelism at such axis, but it will be sufficient simply if the tool applies a pressure, thrust, or blow to the upper ends of the bushing members resulting in their being displaced downward from their normal position in their cooperating guides F.

Obviously, in use, the driving head 5 and the upper hood portions 3, both individually

and in cooperation with each other, serve to protect the valve-head B against injury by a misdirected hammer blow. This is not of great importance because such valve-heads B together with their stems C are quite inexpensive and often are replaced anyway during the overhauling of the engine, but it is an incidental advantage in that it affords protection where it is desired to replace the valve in the engine for further use.

The drawing forming part of this application as made from an actual full-size tool that has been thoroughly and successfully tested and used for the removal of the valve-stem bushings from the guides of automobile engines of the type referred to, Fig. 1 being drawn to a scale five-sixths of the actual size of said actual physical embodiment of the tool, and the remaining figures are on a scale five-elevenths of the actual full size of the actual tool, though of course in Fig. 2 and Fig. 3 there has been no attempt to retain any definite scale relation or proportion between the engine block fragmentarily indicated and the tool.

We claim:

1. A poppet-valve bushing remover comprising a recessed driving head having the walls of said recess vertically slotted in transverse registry and two opposed stiffly resilient sheet metal thrust members having their upper portions substantially parallel and substantially in contact and adapted to be slidably received in the recess of said driving head and held by said head against spreading, said head and members being formed with interengaging means to prevent relative swinging movement between said members about the pin, and a pin extending through said head and the interposed portions of said thrust members and slidably in said slotted head, each said thrust member having a lower shank portion formed in substantial alignment with its upper portion and provided with a radially inner arcuate face adapted to engage the opposed cylindrical face of the valve-stem, a lower hood portion extending upwardly and outwardly at an angle of approximately 45 degrees from its point of emergence with said shank portion, and an upper hood portion extending upwardly and inwardly at an angle of approximately 90 degrees from its point of emergence with said lower hood portion and merging with the upper end portion of the said thrust member, the respective hood portions of the respective thrust members being opposed to each other in assembled operative relation and together constituting a hood accommodating the valve-head when the shank portions of said members are respectively on opposite sides of an intervening valve-stem, and the lower ends of said shank portions being adapted to engage the opposed end face of said bushing and to transmit thereto

- the force of hammer blows exerted on the driving head, all portions of each said thrust member being arcuate in cross section at all points and the joint between each two adjacent portions being arcuate in form. 5
2. A poppet-valve bushing remover comprising a recessed driving head having the walls of said recess vertically slotted in transverse registry, and two opposed stiffly resilient sheet metal thrust members having their upper portions substantially parallel and substantially in contact and adapted to be slidably received in the recess of said driving head and held by said head against spreading, and a pin extending through said head and the interposed portions of said thrust members and slidably in said slotted head, each said thrust member having a lower shank portion formed in substantial alignment with its upper portion and provided with a radially inner arcuate face adapted to engage the opposed cylindrical face of the valve-stem, a lower hood portion extending upwardly and outwardly from its point of emergence with said shank portion, and an upper hood portion extending upwardly and inwardly from its point of emergence with said lower hood portion and merging with the upper end portion of the said thrust member, the respective hood portions of the respective thrust members being opposed to each other in assembled operative relation and together constituting a hood accommodating the valve-head when the shank portions of said members are respectively on opposite sides of an intervening valve-stem, and the lower ends of said shank portions being adapted to engage the opposed end face of said bushing and to transmit thereto the force of hammer blows exerted on the driving head. 10
- 15 3. A bushing remover comprising a recessed driving head and two opposed stiffly resilient sheet metal thrust members having their upper portions substantially parallel and substantially in contact and adapted to be slidably received in the recess of said driving head and held by said head against spreading, and a pin extending through said head and the interposed portions of said thrust members and slidably in said slotted head, each said thrust member having a lower shank portion formed in substantial alignment with its upper portion and provided with a radially inner arcuate face adapted to engage the opposed cylindrical face of the valve-stem, a lower hood portion extending upwardly and outwardly from its point of emergence with said shank portion, and an upper hood portion extending upwardly and inwardly from its point of emergence with said lower hood portion and merging with the upper end portion of the said thrust member, the respective hood portions of the respective thrust members being opposed to each other in assembled operative relation and together constituting a hood accommodating the valve-head when the shank portions of said members are respectively on opposite sides of an intervening valve-stem, and the lower ends of said shank portions being adapted to engage the opposed end face of said bushing and to transmit thereto the force of hammer blows exerted on the driving head. 20
- 25 4. A bushing remover comprising a recessed driving head and two opposed sheet metal thrust members having their upper portions substantially parallel and adapted to be slidably received in the recess of said driving head and held by said head against spreading, each said thrust member having a lower shank portion provided with a radially inner arcuate face adapted to engage an opposed cylindrical face of an intervening element, a lower hood portion extending upwardly and outwardly from its point of emergence with said shank portion, and an upper hood portion extending upwardly and inwardly from its point of emergence with said lower hood portion and merging with the upper end portion of the said thrust member, and the lower ends of said shank portions being adapted to engage the opposed end face of said bushing and to transmit thereto the force of hammer blows exerted on the driving head. 25
- 30 5. Means for removing valve guides comprising a pair of longitudinally grooved thrust members adapted to embrace a valve-stem and having upper portions extending longitudinally in substantial contact with each other and formed with intermediate opposed portions adapted to straddle a valve-head, in combination with a driving head adapted to slidably receive said upper portions of said thrust members. 90
- 35 6. Means for removing valve guides comprising a pair of longitudinally grooved thrust members adapted to embrace a valve-stem and having upper portions extending longitudinally in substantial contact with each other and formed with intermediate opposed portions adapted to straddle a valve-head, in combination with a driving head adapted to slidably receive said upper portions of said thrust members, said intermediate portions forming a protective hood for the valve-head. 100
- 40 7. Means for removing valve guides comprising a pair of longitudinally grooved thrust members adapted to embrace a valve-stem and having upper portions extending longitudinally in substantial contact with each other and formed with intermediate opposed portions adapted to straddle a valve-head, in combination with a driving head adapted to slidably receive said upper portions of said thrust members, said intermediate portions and said driving head cooperating to protect the valve-head against a misdirected hammer blow. 110
- 45 8. Means for removing bushings, said means comprising a pair of longitudinally 120
- 50 9. Means for removing bushings, said means comprising a pair of longitudinally 125
- 55 10. Means for removing bushings, said means comprising a pair of longitudinally 130
- 60 11. Means for removing bushings, said means comprising a pair of longitudinally
- 65 12. Means for removing bushings, said means comprising a pair of longitudinally
- 70 13. Means for removing bushings, said means comprising a pair of longitudinally
- 75 14. Means for removing bushings, said means comprising a pair of longitudinally
- 80 15. Means for removing bushings, said means comprising a pair of longitudinally
- 85 16. Means for removing bushings, said means comprising a pair of longitudinally
- 90 17. Means for removing bushings, said means comprising a pair of longitudinally
- 95 18. Means for removing bushings, said means comprising a pair of longitudinally
- 100 19. Means for removing bushings, said means comprising a pair of longitudinally
- 105 20. Means for removing bushings, said means comprising a pair of longitudinally
- 110 21. Means for removing bushings, said means comprising a pair of longitudinally
- 115 22. Means for removing bushings, said means comprising a pair of longitudinally
- 120 23. Means for removing bushings, said means comprising a pair of longitudinally
- 125 24. Means for removing bushings, said means comprising a pair of longitudinally
- 130 25. Means for removing bushings, said means comprising a pair of longitudinally

grooved thrust members adapted to embrace a cylindrical element and having upper portions extending longitudinally in substantial contact with each other and formed with intermediate opposed portions adapted to straddle an enlarged part, in combination with a driving head adapted to slidably receive said upper portions of said thrust members.

5 10 In testimony whereof, we have signed our names to this specification at Lancaster, Pennsylvania, the 28th day of May, 1931.

HARRY W. KULP.
